CLAIM

The ornamental design for a dresser component for a grindstone, as shown and described.

DESCRIPTION

FIG. 1 is a front view of a dresser component for a grindstone in accordance with an embodiment of the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof; and;

FIG. 8 is a referential view showing the state in use of the dresser component for a grindstone.

The broken lines shown in the referential views represent portions of the dresser component for a grindstone that form no part of the claimed design.

1 Claim, 5 Drawing Sheets---
